(57) **CLAIM**

The ornamental design for an electric toothbrush set, as shown and described.

DESCRIPTION

FIG. 1 is a perspective view of a toothbrush of the electric toothbrush set showing my new design, shown separately to show aspects of the design that are not visible when combined.

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a toothbrush case of the electric toothbrush set showing my new design, shown separately to show aspects of the design that are not visible when combined.

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a perspective view of the electric toothbrush set, shown in use with the toothbrush received in the toothbrush case; and,

FIG. 17 is an exploded perspective view of the toothbrush case of the electric toothbrush set.

The broken lines in the drawings depict portions of the electric toothbrush set that form no part of the claimed design.
